UNITED STATES PATENT OFFICE.

THOMAS WILLIAM HOLT, OF STALEYBRIDGE, ENGLAND.

YARN-CLEANING DEVICE.

1,190,169.

Specification of Letters Patent.

Patented July 4, 1916.

Application filed May 5, 1916. Serial No. 95,614.

To all whom it may concern:

Be it known that I, THOMAS WILLIAM HOLT, a subject of the King of Great Britain and Ireland, residing at 79 Willwood Terrace, Wakefield Road, Staleybridge, in the county of Chester, England, engineer, have invented new and useful Improvements in Yarn-Cleaning Devices, of which the following is a specification.

- 10 This invention relates to improvements connected with or applicable to tension imparting or clearing mechanism used on machines for dealing with yarn, thread, and the like.
- 15 In particular it relates to means for use in combination or in connection with that class of yarn tensioning or clearing device wherein is employed one or more disks or clearing devices which is or are rotatable or 20 movable relatively.

The ordinary or best known type of tension or drag device at present employed includes a suitable guide or guides and a drag board covered with flannel or such like, and 25 this has been extensively used, and while considerable fly or waste is produced by this system, the method makes piecing-up and threading a very simple matter.

With the rotatable tension disks or 30 devices, while better yarn and less waste is produced, the employment of the rotatable tension devices gives more work to the attendant because it is necessary to pass the yarn or ends between the rotatable parts 35 and the yarn must be accurately guided and directed to that end. Now, according to my invention, I provide, in combination with said tension devices, means which insure that the yarn is automatically directed 40 between the rotatable devices, that is, by the mere pressing down of the yarn between co-acting guides, the same is directed into position exactly ready for entrance between the rotatable devices, with result, that, im-

45 mediately the pull or tension comes on the yarn, the same necessarily passes into position and between the rotatable devices which are to exercise the clearing and tensioning effect.

50 The object in view can be carried out by various simple devices, as for example, by using oppositely disposed inclined planes one front and the other back of the tension device, the planes deflecting the yarn and 55 throwing it in exact alinement with the entrance level at which the meeting faces

contact. Provision is also made whereby the yarn can slip below one or both of said inclined planes, with the idea, that, immediately tension comes on the yarn, the same 60 is drawn into a more or less straight path and so is properly disposed between the rotatable or other tension devices and continues to pass in proper fashion until the end again breaks.

65 In the attached drawings I illustrate how my invention can be carried into practical effect, the said drawing showing a rotatable disk tension device with directing contrivances which deflect and guide the yarn in 70 such manner that exceedingly rapid and almost automatic threading can be effected.

75 Referring to the drawings; Figure 1 shows in side elevation my complete "self-threading" tension device. Fig. 2 is a plan view of Fig. 1. Fig. 3 is a section. Fig. 3^a is a detail view. Fig. 4 shows a separate plan view of the carrying base or cast-iron supporting bracket. Fig. 5 is a detail view 80 of the rear wire. Fig. 6 is a detail view of a modified form of rear wire.

85 The cast-iron bracket *a* is adapted to be fixed to a rail or support such as *b* and is held by a pinching screw *a'* or otherwise. To the bracket *a* is attached a slotted steel guide plate *c* and said bracket *a* has a forward bifurcated portion *a*². The bracket has also a cast projection or upstanding portion *a*³ and is bored for the bearing pin *e* to 90 which is fixed the lower disk *f* which preferably has a shallow central depression on its upper face. Resting upon the lower disk *f* is the upper or loose dished disk *g* which is adapted to receive weights or washers *g'*.

95 I find that for the purpose of my invention, wire deflecting devices serve well and these I preferably apply to or carry from the cast-iron brackets. In the case of ascending yarn, I use a wire device which has an upright limb *h* and is then bent downward and forward, as at *h'*, to produce an inclined directing plane. The upright limb *h* is fixed in a hole *a*⁶ in the cast-iron bracket *a*, and held by a pinching screw *h*³, or otherwise, and, the lower end of the inclined limb *h'* is bent in, a little at *h*². This inclined limb does not reach down to the cast-iron bracket *a* but terminates about the line with the meeting or contacting faces of the two disks *f* and *g*. At the other ends of the 100 cast-iron bracket *a* I apply another, bent wire which produces an inclined or curved

limb which is oppositely disposed to the other inclined limb of the first bent wire. In the drawing, I show a curved limb *i* (see more particularly Fig. 5). This limb may be bent or provided with a loop or eye, below which the yarn can pass to prevent lifting of the upper disk. I have not however found this necessary. The wire of the limb or loop *i* is bent and continued downward so that the complete guide can be fixed by pushing the two ends into holes *a*⁴ *a*⁴ in the cast-iron bracket as shown. I may produce both the yarn directing planes from one length of wire or in the form of a complete device readily attachable to the cast-iron bracket.

My invention includes directing inclines, guides, or planes, so combined with the tension motion bracket, that by the pressing or holding of the yarn toward the tension devices, said yarn is automatically deflected and thrown into a position which is tangential to the tension devices, and, at the right moment, that is, when the yarn is in the exact plane for the purpose, the same is freed from the influence of one or both of said inclines, guides, or planes, or the like. As thus liberated from the influence of said inclines, &c., the pull or tension of the yarn directs the "end" properly between the rotary or other tension or clearing devices instantly and without requiring skill, the inclines, &c., themselves insuring automatic deflection and direction.

In the drawings, the yarn is shown as passing upward, then through the tension motion and over the bar or ledge *a*⁵ and around the post constituted by the wire *i* to an ordinary drop wire *j* and then upward again, but the manner of directing the yarn would vary very considerably.

It will be understood, that my improvements are applicable to a variety of tension or clearing devices having rotatable or disk like elements and the exact construction of the directing inclines, guides, or the like would require modification according as one or more ends are dealt with, and according as to whether the yarn or the like passes up or down to the winding on or like devices. When the yarn would pass upward, I might provide the rear wire *i* with an overhanging hook or curl such as *i'* see Fig. 6. I may dish or recess the bottom or under face of the lower disk *f* and I may cut a number of holes or slots in said lower disk *f* as shown at *f'* in the detail Fig. 3^a.

I declare that what I claim is:

A yarn tension device having a bracket, a slotted steel guide attached thereto, a forward bifurcated extension on said bracket having a laterally extending lug, rotatable adjacent tension disks, a deflecting guide adjustably secured in said lug in advance of the tension disks and to one side thereof, said guide comprising a wire having a limb that extends upwardly then downward and forward and then slightly curvally inwardly to produce an inclined directing plane terminating in line with the contacting faces of the disks, and a double curved deflecting guide in rear of said disks, said guides adapted to throw the yarn tangentially to the disks and thereafter permitting sufficient release to effect threading.

In testimony whereof I have signed my name to this specification in the presence of two subscribing witnesses.

THOMAS WILLIAM HOLT.
